LATCH

Francis M. Hogg, Erie, Pa., assignor to General
Electric Company, a corporation of New York

Application January 4, 1938, Serial No. 183,397

7 Claims. (CL 292—173)

My invention relates to latches for refrigerator cabinets or the like.

It is an object of my invention to provide an improved latch comprising a minimum number of parts, which is readily assembled and economical to manufacture, and which has a finished and pleasing appearance.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing in which Fig. 1 is a fragmentary perspective view of a portion of the frame and door of a refrigerator cabinet provided with a latch embodying my invention; Fig. 2 is an enlarged side elevational view, partly in section, of the latch shown in Fig. 1; and Fig. 3 is a fragmentary perspective view of the operating mechanism of the latch shown in Fig. 2.

Referring to the drawing, in Fig. 1 I have shown a portion of a household type refrigerator cabinet 10 having an opening in the front wall thereof closed by a door 11. The refrigerator cabinet 10 comprises a metal outer shell 12 and a sheet metal inner liner 13 spaced therefrom by a layer of heat insulation 14. The marginal edges of the shell 12 and the liner 13 are flanged toward each other adjacent the opening in the front wall of the refrigerator cabinet 10 and are joined together by a strip of thermally resistant material 15. The front wall of the shell 12 extending about the margin of the opening in the refrigerator cabinet 10 constitutes a door frame to which the door 11 is hinged. The door 11 comprises a sheet metal outer wall 16 and a sheet metal inner wall 17 spaced therefrom by a layer of heat insulation 18. The marginal edges of the outer wall 16 and the inner wall 17 are flanged toward each other and joined together by a strip of thermally resistant material 19. The door 11 is also provided with a marginal flange 11a projecting over a portion of the front wall of the shell 12. A gasket 20 is secured to the inner face of the marginal flange 11a of the door 11 and provides a seal between the marginal flange of the door and the front wall of the shell 12. A latch 21 comprising cooperating parts carried by the outer edge of the marginal flange of the door 11 and the front wall of the shell 12 is provided in order to retain the door in a closed position.

The latch 21 comprises a support in the form of

an elongated hollow casing 22 provided with integral upper and lower tabs 23 secured to the outer edge of the marginal flange 11a of the door 11 by screws 24 extending through openings therein and threaded into a portion carried by the marginal flange of the door 11. A latch bolt 25 is slidably arranged in the casing 22 and is adapted to move in a vertical direction through an opening 26 formed in the lower portion of the casing into extended and retracted positions. The latch bolt 25 comprises a head 27 and two upwardly extending spaced-apart arms 28 secured thereto by pins or rivets 29. A member 30 is arranged within the casing 22 adjacent the upper portion thereof and is pivoted to the walls of the casing 15 by a pin 30a. The member 30 is movable by a handle 31 in opposite directions about the pivot 30a within the casing 22.

A lost motion connection is provided between the inner end of the member 30 and the inner end 20 of the latch bolt 25 in order to provide for upward movement of the latch bolt independently of the member 30 and its handle 31. This connection also provides for retraction of the latch bolt by actuation of the handle 31, and comprises 25 a slot 32 formed in the inner end of the member 30 and a pin 33 extending therethrough and secured in openings formed in the inner ends of the upwardly extending arms 28 of the latch bolt 25. An arrangement for moving the latch bolt 30 into extended latching position and for moving the member 30 in a counterclockwise direction about the pivot pin 30a is provided which includes two co-operating thrust members 34 and 35 and a helical compression spring 36. The 35 thrust members 34 and 35 are arranged in sliding engagement with each other, one end of each thrust member being slotted and the slotted ends of the thrust members being arranged in interfitting relation. The other end of the thrust 40 member 34 is pivoted to a pin 37 extending between the spaced apart arms 28 of the latch bolt 25 and the other end of the thrust member 35 engages a recess 38 formed in the outer end of the member 30. The helical compression spring 45 36 is arranged about the thrust members 34 and 35, one end of the spring engaging a shoulder 39 formed on the thrust member 34 and the other end of the spring engaging a shoulder 40 formed on the thrust member 35. Movement of the 50 member 30 in a counter-clockwise direction, as viewed in Fig. 2, about the pivot pin 30a is limited by the engagement between a flange 41 provided on the member 30 and the upper portion of the casing 22. The depth of the slots provided in 55

the thrust members 34 and 35 determines the amount of movement of the member 30 in clockwise direction, that is, the sliding engagement between members 34 and 35 will continue until the bottom of the slot in one member comes into engagement with the bottom of the slot in the other member. The slots in the thrust members 34 and 35 are made wide enough to provide freedom of movement between thrust members 34 and 35, but narrow enough to prevent any appreciable lateral movement of the thrust members. This construction, together with the arrangement for limiting clockwise rotation as described above, cooperates to prevent any toggle action as well as to limit the clockwise rotation. In other words, spring 36 and thrust members 34 and 35 are fitted together in such a manner that they will always remain to the right of a line drawn through pivots 30a and 31, as viewed in Fig. 2. Thus the force in compression is always effective to tend to force member 30 in a counter-clockwise direction about the pivot 30a. The member 30 is also provided with an upwardly extending portion constituting the handle 31 for moving the member 30 about the pivot pin 30a in order to move the latch bolt 25 into a retracted position. Preferably, the member 30 and the upwardly extending portion 31 thereof are formed integral. The outer surface of the upwardly extending handle 31 is arranged in alignment with the outer surface of the casing 22 and forms a continuation thereof in order to give the latch an unbroken finished appearance.

A metal keeper 43 having a downwardly extending flange 44 is secured to the front wall of the shell 12 below the casing 22. The keeper 43 is provided with a recess 45 therein which is adapted to receive the lower end of the head 27 of the latch bolt 25 in order to retain the door 11 in closed position.

In order to open the door 11 the handle 31 of the latch 21 is moved outwardly with respect to the door causing the member 30 to move in a clockwise direction, as viewed in Fig. 2, about the pivot pin 30a. This movement of the member 30 is transmitted through the pin and slot connection between the inner end of the latch bolt 25 and the inner end of the member 30 and causes the latch bolt 25 to be moved into retracted position moving the head 27 thereof out of engagement with the recess 45 in the keeper 43. The door 11 may then be moved to an open position. Movement of the member 30 in a clockwise direction, as viewed in Fig. 2, about the pivot pin 30a also compresses the spring 36 interposed between the latch bolt 25 and the outer end of the member 30. When the handle 31 is released the spring 36 moves the latch bolt 25 into extended position and moves the member 30 in a counterclockwise direction about the pivot pin 30a, the movement of the member 30 in a counter-clockwise direction about the pivot pin 30a being limited by the engagement between the stop 41 carried by the member 30 and the upper end of the casing 22.

As the door 11 is moved toward a closed position, an inclined surface 27a provided on the head 27 of the latch bolt 25 engages an inclined surface 43a provided on the keeper 43 and forces the latch bolt 25 into retracted position. This movement of the latch bolt 25 compresses the spring 36. When the door 11 is moved into fully closed position, the head 27 of the latch bolt 25 is moved into the recess 45 in the keeper 43 by the compression spring 36. Due to the lost-mo-

tion connection between the inner end of the latch bolt 25 and the inner end of the member 30, the latch bolt 25 is free to move into retracted position upon the engagement between the inclined surface 27a provided on the head 27 of the latch bolt 25 and the inclined surface 43a provided on the keeper 43 independent of movement of the member 30 about the pivot pin 30a. Also, due to this connection, movement of the latch bolt 25 into extended position by the spring 36 is independent of movement of the member 30 about the pivot pin 30a. Thus, movements of the latch bolt 25 caused by closing the door 11 are not transmitted to the member 30 and the handle 31 carried thereby.

In order to provide a smooth sliding action between the inclined surface 27a provided on the head 27 of the latch bolt 25 and the inclined surface 43a provided on the metal keeper 43, the head 27 is formed of some non-metallic substance such, for example, as a resinous condensation product having a suitable filler.

While I have shown a particular embodiment of my invention in connection with a household type refrigerator cabinet, I do not desire my invention to be limited to the construction shown and described and I intend in the appended claims to cover all modifications within the spirit and scope of my invention.

What I claim as new and desire to secure by Letters Patent of the United States is:—

1. A latch comprising a support, a latch bolt slidably carried by said support and movable into extended and retracted positions, a member pivoted to said support and movable in opposite directions about said pivot, a connection between one end of said member and the inner end of said bolt, means including a compression spring interposed between said bolt and the other end of said member for moving said bolt into extended position and for moving said member in one direction about said pivot, and means adapted to move said member in the opposite direction about said pivot for moving said bolt into retracted position.

2. A latch comprising a support, a latch bolt slidably carried by said support and movable into extended and retracted positions, a member pivoted to said support and movable in opposite directions about said pivot, a lost motion connection between one end of said member and the inner end of said bolt, said connection allowing movement of said bolt into retracted position independent of movement of said member about said pivot, means including a compression spring interposed between said bolt and the other end of said member for moving said bolt into extended position and for moving said member in one direction about said pivot, and means including a handle carried by said member and adapted to move said member in the opposite direction about said pivot for moving said bolt into retracted position.

3. A latch comprising a support, a latch bolt slidably carried by said support and movable into extended and retracted positions, a member pivoted to said support and movable in opposite directions about said pivot, a connection between one end of said member and the inner end of said bolt, said connection including a slot in said member and a pin carried by said bolt and allowing movement of said bolt into retracted position independent of movement of said member about said pivot, means including a compression spring interposed between said bolt and

the other end of said member for moving said bolt into extended position and for moving said member in one direction about said pivot, and means adapted to move said member in the opposite direction about said pivot for moving said bolt into retracted position.

4. A latch comprising a support, a latch bolt slidably carried by said support and movable into extended and retracted positions, said latch bolt comprising a head and two spaced apart arms extending therefrom, a member pivoted to said support and movable in opposite directions about said pivot, the inner ends of the arms of said bolt being arranged on opposite sides of one end of said member and connected thereto, means including a spring for moving said bolt into extended position and for moving said member in one direction about said pivot, one end of said spring being pivotally mounted between the arms of said bolt and the other end of said spring acting upon the other end of said member, and means adapted to move said member in the opposite direction about said pivot for moving said bolt into retracted position.

5. A latch comprising a support, a latch bolt slidably carried by said support and movable into extended and retracted positions, said latch bolt comprising a head and two spaced apart arms extending therefrom, a member pivoted to said support and movable in opposite directions about said pivot, means including a slot in one end of said member and a pin carried between the inner ends of the arms of said bolt for providing a connection therebetween, said connection permitting movement of said bolt into retracted position independent of movement of said member about said pivot, means including a spring for moving said bolt into extended position and for moving said member in one direction about said pivot, one end of said spring being pivotally mounted between the arms of said bolt and the other end of said spring acting upon the other end of said member, and means including a handle carried by said member and adapted to move said mem-

ber in the opposite direction about said pivot for moving said bolt into retracted position.

6. A latch comprising an elongated hollow casing, a latch bolt slidably arranged in said casing and movable into extended and retracted positions, a member arranged in said casing and pivoted to said casing, said member being movable in opposite directions about said pivot, a connection between one end of said member and the inner end of said bolt, means including a compression spring interposed between said bolt and the other end of said member for moving said bolt into extended position and for moving said member in one direction about said pivot, and means including a handle carried by said member and adapted to move said member in the opposite direction about said pivot for moving said bolt into retracted position, said handle normally extending in the same direction as said casing and forming a continuation thereof to give said latch an unbroken appearance.

7. In a door construction including a door, a door frame therefor and a keeper carried by said door frame, a latch comprising a hollow casing carried by the edge of said door, a latch bolt slidably arranged in said casing and movable in a vertical direction into extended and retracted positions, said bolt extending into a recess formed in said keeper in said extended position, a member arranged in said casing and pivoted to said casing, said member being movable in opposite directions about said pivot, a connection between one end of said member and the inner end of said bolt, means including a compression spring interposed between said bolt and the other end of said member for moving said bolt into extended position and for moving said member in one direction about said pivot, and means including an upwardly extending handle carried by said member and adapted to move said member in the opposite direction about said pivot for moving said bolt into retracted position.

FRANCIS M. HOGG.
